(57) **CLAIM**

The ornamental design for a measuring cup, as shown and described.

DESCRIPTION

FIG. 1 is a top, right side perspective view of a measuring cup showing our new design;

FIG. 2 is a front elevation of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of FIG. 1;

FIG. 9 is a cross-sectional view of FIG. 4; and,

FIG. 10 is a perspective view of the measuring cup of FIG. 1, shown with an additional environmental element.

The broken lines in the drawings depict portions of the measuring cup that form no part of the claimed design.

1 Claim, 10 Drawing Sheets
